SCARF

Thekla L. Ofria, New Orleans, La.

Application April 20, 1950, Serial No. 9,358

Term of patent 14 years

(Cl. D3—12)

To all whom it may concern:

Be it known that I, Thekla L. Ofria, a citizen of the United States, residing in New Orleans, in the parish of Orleans and State of Louisiana, have invented a new, original, and ornamental Design for a Scarf, of which the following is a specification, reference being made to the accompanying drawings, forming a part thereof.

Fig. 1 is a front view showing one half of a scarf.

Fig. 1a is a front view showing the other half thereof, the whole showing my new design.

The essential features of my design reside in the portions shown in full lines.

I claim:

The ornamental design for a scarf, substantially as shown and described.

THEKLA L. OFRIA.
